CUFF LINK

Karl Albrecht, Maplewood, N. J., assignor to
Forstner Chain Corporation, a corporation of
New Jersey

Application December 7, 1949, Serial No. 131,607

2 Claims. (Cl. 24—97)

1

The present invention relates to the jewelry art, and has particular reference to a novel construction for a cuff link.

The principal object of the invention is to provide an improved construction for a cuff link having a fixed ornamental head and a movable retainer head.

Another object of the invention is to provide a novel arrangement for selectively releasably holding the movable retainer head in different positions.

With the above and other objects and advantageous features in view, the invention consists of a novel arrangement of parts more fully disclosed in the detailed description following, in conjunction with the accompanying drawings, and more specifically defined in the claims appended thereto.

In the drawings,

Fig. 1 is a perspective view of a cuff link embodying the invention;

Fig. 2 is a perspective view of the center post thereof;

Fig. 3 is an enlarged section on the line 3—3 of Fig. 1;

Fig. 4 is an enlarged side view of the movable retainer head;

Fig. 5 is a perspective view of one cam element; and

Fig. 6 is a perspective view of one cam element spring plate.

It has been found desirable to provide a cuff link which utilizes a snap cam and groove device for retaining a movable head in selected position relative to a fixed center post, in order to obtain a rigid holding for a long, effective life. To this end, it is preferred to mount the movable parts of the snap cam and groove device within the movable head, whereby the center post may be made of rigid material.

Referring to the drawings, the cuff link 10 includes a center post 11 in the form of a U, with sides 12, 13 and a base 14; an ornamental head 15 is secured to the base 14, by soldering or in any other suitable manner, and a movable head 16 is pivotally mounted to swing between the post sides 12, 13, as hereinafter explained. The inner surface 17 of each side is provided with a transverse groove 18 and a crossing longitudinal central groove 19, and each side has a pivot pin passage 20 therethrough as illustrated in Fig. 2, at the point of crossing of the grooves 18 and 19.

The movable head 16 is tubular and generally square, and includes a central tube 21, preferably

square, and having longitudinal slots 22, 23 on opposite sides thereof. Positioned within the tube 21 are two arcuate spring plates 24, see Fig. 6, having central openings 25 through which a pivot pin 26 extends; the spring plates are in opposed relation with their ends contacting, as shown in Fig. 3.

A cam element 27, see Fig. 5, of hardened stock, is positioned on the outer surface of each spring plate and includes a base 28 shaped to conform to the spring plate contour and a divided cam 29 in the form of a longitudinal upstanding aligned arcuate ribs 30, 31, the base having an opening 32 between the ribs, whereby the pivot pin 26 passes through the openings 32 and the passages 20 of the central post arms and is headed over, see Fig. 3, to lock the parts together. The cam ribs 30, 31 are aligned with and extend through the slots 19, as shown in Fig. 4, and the ends of the tube 21 are closed by ornaments 33, 34, of any desired type.

When the parts are assembled as shown in Figs. 1 and 3 and the movable head is turned to be in alignment with the center post sides, the cam ribs 30, 31 move and snap seat into the longitudinal grooves 18; when the movable head is turned at right angles to the center post, the cam elements move against the resilience of the spring plates and snap seat into the transverse grooves 18.

If desired, one cam element may be fixed in place, but it is preferred to have both cam elements move, as the resulting releasable lock is strong.

Although I have described a specific constructional embodiment of the invention, it is obvious that changes in the size, shape and arrangement of the parts may be made to suit the requirements for different cuff link designs, without departing from the spirit and the scope of the invention as defined in the appended claims.

I claim:

1. In a cuff link, a U-shaped center post having spaced sides and a base, an ornamental head secured to said post base, the inner surface of each side having a transverse groove and a crossing longitudinal groove, each side having a pivot pin passage at the point of crossing of the grooves, a pivot pin seated in said passages, a hollow movable head pivotally mounted on said pivot pin, the sides of said head contiguous the inner surfaces of the post sides having narrow slots, cam elements in said head having cam ribs extending through said slots, and arcuate spring plates in said head in opposed relation

with their ends contacting and urging said cam elements outwardly to selectively seat in the side grooves as the head is turned, said cam elements and spring plates having openings for passage of the pivot pin therethrough.

2. In a cuff link, a U-shaped center post having spaced sides and a base, an ornamental head secured to said post base, the inner surface of each side having a transverse groove and a crossing longitudinal groove, each side having a pivot pin passage at the point of crossing of the grooves, a pivot pin seated in said passages, a hollow movable head pivotally mounted on said pivot pin, the sides of said head contiguous the inner surfaces of the post sides having narrow slots, cam elements in said head having arcuate rear surfaces and projecting cam ribs extending through said slots, and arcuate spring plates in

said head in opposed relation with their ends contacting and engaging the arcuate rear surfaces of the cam elements and urging said cam elements outwardly to selectively seat in the side grooves as the head is turned, said cam elements and spring plates having openings for passage of the pivot pin therethrough.

KARL ALBRECHT.
